ROLLER SKATE

Charles Z. Shye, New York, N. Y.

Application August 1, 1941, Serial No. 404,987

12 Claims. (Cl. 280—11.27)

This invention relates to new and useful improvements in roller skates.

The invention proposes a roller skate construction which overcomes numerous defects inherent in present day constructions and which does not embody any new or additional defects not inherent in prior constructions.

An important object of this invention is to build a new roller skate which has a chassis upon which the front and rear trucks are mounted.

In prior constructions the foot plates were used to join the front and rear trucks together as a unit, but with this new construction the skate can stand on its wheels without the presence of the foot plates. In the new construction the foot plates are mounted on the chassis, and the chassis is even used to assist in supporting the shoe clamps of the skate. Thus the entire skate is built on the chassis.

It is proposed to so construct the chassis and trucks of the skate to make skating actions possible without side slipping or back and forward motion or wobbling of the trucks of the skate. It is claimed that the new chassis and the hangers of the trucks are important contributions to the roller skate. The chassis removes countless parts now generally used in the best, as well as the cheapest skate. It totally eliminates riveting of these numerous parts. The new structure not only eliminates many operations and parts, but the one piece chassis gives strength, durability, simplicity and beauty of line, and cuts down noise of all connecting parts, making the skate practically noiseless. It also makes the skate the safest created, since the history of skating, due to the absence of a great many parts and their probable looseness from their riveted connections due to vibration, wear, breakage, or flaws in any of the connections of the parts.

This invention further contemplates supporting each skate hanger, or truck in a certain way. It is proposed to support the hanger, or truck at three different distinct points, in a manner to give perfect alignment and to make skating action easy, comfortable, and sure. It is proposed to so support the new hangers and trucks to eliminate the necessary tightening or loosening of the present day kingpins to adjust the actions of the hangers and trucks. The new construction removes excessive play, thus cutting down excessive wear and tear on the cushions, kingpins, and hanging points, or the breaking and bending of supported points or parts. The new construction proposes a certain relationship between each cushion and kingpin, making the new skate par-

ticularly noiseless. Each hanger and truck will be supported in a perfectly balanced way on the chassis, which is also perfectly balanced, making a perfectly balanced skate and eliminating breakage which generally occurs in a skate due to unbalanced parts. The new construction removes all hazards of too much rigidity, and removes the tendency of wobbling from left to right, or towards one or another point beyond the control of the skater. The new soft rocking action makes it easy on the skater's ankles, leg muscles, and makes skating much more effortless for both the experienced skater and the beginner. It makes the trucks of the skate more secure and answerable instantaneously both to the direction of the foot and the shifting or balancing of the body. Furthermore, the invention proposes a new style and unique design of the cushion which will add to the ease of direction and the rocking movement of each skate truck, thus removing drag between shifting parts and wear and tear on all the connecting parts and enabling the skater to perform the most difficult figure work—circles, dance steps, etc., simply, and with more perfect poise and without strain upon skater or skate. It is proposed that each cushion be of oval shape in transverse cross section and that contacting parts be similarly shaped. The unique oval-like shape gives extra spread to the front and back contact points of the cushion on its seat on the hanger. Because of these improvements the skate in its action will be instantaneous at the command of the skater's foot and shifting of the body, thus removing drag and stress upon component parts of the skate, enabling the skater to perform the most difficult types of skating without strain and without excessive effort, loss of motion or balance.

Furthermore it is proposed that the seats of the hangers be formed with elongated openings which give added room to the kingpins, and adds considerable ease and support to the central rocking motions of the hangers which is so vital in the performance of figure skating and dancing, and perfect control and maneuverability of skating.

A new construction is also proposed respecting the kingpin. Heretofore, the kingpin had a head at the bottom and screw threads at the top which threadedly engaged into a bracket connected with the foot plate. In this old construction it is necessary to screw out, or screw in, the kingpin for controlling the cushioning effect. Such adjustments require guess work as to how many threads of the kingpin are engaging the threads of the bracket. With the old

construction ripping of the threads of the bracket occurred quite frequently. This invention contemplates a new construction in which the kingpin has a head on the top removably mounted in a certain way upon the chassis of the skate, and has threads at the bottom for nuts or supporting members to hold the hanger and truck in position. The new construction eliminates any guesswork as to the number of threads which are engaged. It eliminates the possibility of the threads in the bracket ripping out. It eliminates vibrations and other strains damaging or loosening the kingpin or associated parts, which in the past have caused the larger and more serious accidents in skating.

With the new construction a change of cushion may be made, or any of the component or associated parts removed, by simply removing the lower nut or supporting member, or the complete hanger and truck may then be removed. With the new construction the kingpin may easily be disconnected from the chassis. The parts may be easily reassembled and properly adjusted with a minimum of labor. All adjustments may be made easily with one hand, contrasted with prior constructions in which one hand usually was needed to operate an implement to hold a nut while the other hand was needed to turn the kingpin with another implement.

The invention also contemplates the use of a small auxiliary cushion between the kingpin and bottom nut, in addition to the usual cushion on the kingpin above the seat of the hanger. It is proposed that in addition to said auxiliary cushion and nut, that a screw and washer be mounted on the bottom of the kingpin to hold and support the nut if it becomes loose due to vibrations. The auxiliary cushion acts as a buffer between the nut and a washer placed beneath the bottom seat of the hanger. It aids considerably in removing drag between washer and nut and adjacent parts in permitting the washer to ride over the shoulders on the bottom seat of the hanger. It assists in drawing the entire hanger and truck back to normal position in its rocking motion from side to side, and eliminates the clash between the locking and moving parts. It is proposed that the auxiliary cushion be of fiber and rubber material or other material, which will also act as a lock device, and its resiliency will aid the cushion to do its work much easier, surer, and simpler, saving wear and tear on both, giving longer life to the main cushion and component parts, and thus reducing the acoustics, sounds of the clash of metal parts and other parts and noises, particularly created between the skate and floor when skating. It aids greatly in making the skate noiseless.

The invention also proposes a novel construction for preventing the nut or supporting members on the bottom of the kingpin from being lost, which construction is of a nature to have general application on other articles and in other fields.

It is also pointed out that the method of mounting the kingpin on the chassis of the skate may have general application to other articles and other arts. The invention therefore contemplates including such broad aspects of this construction.

Another object of the invention is the construction of an article as described which is simple and durable, and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a roller skate constructed in accordance with this invention.

Fig. 2 is a plan view of the skate shown in Fig. 1 looking in the direction of the line 2-2 thereof, this view being taken directly beneath the foot plates.

Fig. 3 is a transverse sectional view taken on the line 3-3 of Fig. 2.

Fig. 4 is a fragmentary plan view looking in the direction of the line 4-4 of Fig. 1.

Fig. 5 is a fragmentary sectional view taken on the line 5-5 of Fig. 3.

Fig. 6 is a fragmentary enlarged sectional view taken on the line 6-6 of Fig. 4.

Fig. 7 is an enlarged sectional view taken on the line 7-7 of Fig. 4.

Fig. 8 is a fragmentary sectional view taken on the line 8-8 of Fig. 1.

Fig. 9 is a fragmentary enlarged sectional view taken on the line 9-9 of Fig. 1.

Fig. 10 is a fragmentary enlarged sectional view taken on the line 10-10 of Fig. 1.

Fig. 11 is a plan view of one of the hangers used in the skate.

Fig. 12 is a fragmentary sectional view of a portion of the chassis of the skate which supports one of the kingpins of the skate.

The skate, in accordance with this invention, includes a one piece, comparatively flat and balanced chassis 12. This chassis has a front top strip portion 13, a rear top strip portion 14, and an arched central portion 15. A sole plate 16 is mounted on the front top strip portion 13. A heel plate 17 is mounted on the rear top strip portion 14. The arched central portion 15 has front and rear sharp edge portions 18 and 18', respectively which are inclined forwards and rearwards, respectively. The front top strip portion 13 has a front lug portion 20 behind which there is a downwardly directed sharp edge portion 21. The rear top strip portion 14 has a rear lug 22 to the front of which there is a downwardly directed sharp edge portion 23. A front hanger 24 is mounted on the front portion of the chassis 12 and has a front arm 25 provided with a bifurcated portion 26 engaging beneath and against the sharp edge portion 21. The hanger 24 also has a rear arm 27 provided with a bifurcated rear end 28 engaging beneath and against the sharp edge portion 18. The skate is also provided with a rear hanger 24' which has an arm 25' with a bifurcated end 26' engaging beneath and against the sharp edge portion 23. The hanger 24' also has another arm 27' with a bifurcated end 28' engaging beneath and against the sharp edge portion 18'.

The hangers of the skate are held in position with kingpins 34 and nuts 49. Each kingpin 34 is connected with the chassis 12 in a certain way. More specifically, the chassis is formed with a slot 35 for each kingpin, extended inwards from one edge, and having a comparatively narrow outer end 35a and an enlarged inner portion 35b. The kingpin 34 is provided with a head 36 which seats into said enlarged inner portion 35b. The stem

of the kingpin 34 passes out from said smaller outer portion 35a. The slot 35 extends through the chassis 12, from one side to the other. The slot 35 divides off small tits 37 (see Fig. 12) which form anchorage points for the head 36 of the kingpin. A washer 38 engages on the stem or shank of the kingpin 34 and has side portions 38a which are bent over the sides of the chassis 12 to hold the kingpin from slipping out of the slot 35.

Each hanger of the skate has a central seat portion 39 which is of oval shape in plan view, with its major axis extending longitudinally of the skate. A cushion 40 of rubber is mounted on each kingpin and is of a similar oval shape, and rests upon a top concaved shoulder 39a of the seat 39. The seat 39 has an oblong shaped transverse opening 41 (see Fig. 11) which will permit the hanger to pivot laterally on the kingpin. The recessed top shoulder 39a will give the cushion 40 more support at the front portion and at the rear portion of its major axis than at the sides, reducing resistance to lateral pivoting of the hanger. Consequently, when the truck of the skate pivots laterally there will not be so much resistance as in prior constructions. Each hanger is also provided with a transverse tubular portion 42 through which the axle 43 of the truck passes. The skate has a front truck and a rear truck, and each truck comprises a hanger (24 or 24'), an axle 43, and a pair of wheels 44, the details of which will not be given in this specification. However, these wheels may be of the ball bearing type, or other suitable types generally used.

An oval shaped cover plate 45 with edge flanges 45a (see Fig. 3) is mounted on each kingpin and engages the top of each cushion 40. A top nut 46 is threadedly mounted on each kingpin above the cover plate 45 for forming a top abutment for the cushion 40. An auxiliary cushion 47 is mounted upon the bottom of each kingpin. There is a washer 48 on each kingpin above the auxiliary cushion, which engages the bottom shoulder of the seat 39. A bottom nut 49 is threadedly mounted on the kingpin for controlling the compression of said cushions. The auxiliary cushion 47 preferably is a combination of cloth and rubber. A lock device is mounted on the bottom of each kingpin 34 for preventing accidental loss of the bottom nut 49 when loosened by vibration. This lock device includes a bottom washer 50, and a small screw 51 which is threadedly mounted in the bottom of the kingpin.

The sole plate 16 is held in position by several lug portions 52 and 53' which are stamped or formed from the metal or material thereof, and which is connected with the chassis by welding, or with fastening elements or other means. The lug 20 of the chassis 12 is provided with a slot 53 through which the reduced central portion 54 of the usual right and left hand clamp screw 55 passes. This clamp screw 55 is provided with square end portions 56 by which it may be turned with the usual skate key. The sole plate 16 has several strip portions 57 struck or formed from the material thereof and forming tracks slidably supporting the clamp jaws 58. Each strip portion 57 has a projecting end 59 adapted to strike a lug portion 60 of each clamp jaw 58, to limit the clamp to its fully extended position. Each clamp jaw 58 has its lug portion 60 threadedly engaging a section of the clamp screw 55. The arrangement is such that the screw 55 may be turned in one direction to open the clamp, or in

the other direction to close it, and engage the sole of one's shoe.

The chassis 12 is formed with another slot 62 for receiving the heel clamp of the skate. The heel plate 17 of the skate is provided with stamped out lug portions 52 and 53 by which it is attached to the chassis 12. The heel plate 17 is also provided with stamped out portions 57 forming the tracks for the heel clamp jaws 58. In other respects this heel clamp is similar to the sole clamp.

The action of the skate may best be understood by an examination of the drawings and noting that each hanger is supported at three points. The front and rear points include the sharp edge portions of the chassis which permit the truck of the skates to pivot laterally. The central point includes the washer 48 engaging against the bottom of the seat portion 39 of the hanger of the truck. The bottom of each seat portion 39 is rounded along the sides, as shown in Fig. 3, which permits the truck to pivot laterally without drag at this point. A further important feature of the three point support resides in the fact that each truck will be restrained from rattling forwards or rearwards because of the formation of the sharp edge portions, as clearly shown in Fig. 1.

It will readily be seen that each truck cannot move forwards nor rearwards. However, it is free to pivot laterally. The central support, which includes the kingpin 34 and nut 49, permits the truck to pivot laterally, while at the same time the cushions 40 and 47 produces a resilient support for the truck so as to normally tend to hold it in a true balanced central line. When the truck does pivot laterally during skating relative to the chassis, the resiliency of the cushion and the auxiliary cushion will tend to bring the truck back to its aligned position. It should be particularly noted that while the truck pivoting is relatively free, because the washers and other parts on the kingpin will not have to slide relative to each other, thus eliminating drag, it will be quite firmly held, particularly against forwards and rearwards motion.

Each truck may be quickly removed by first removing the holding screw 51 and nut 49 and then slipping the washers and cushions off the kingpin. The parts may be easily replaced. Each kingpin may be removed by first opening the lock washer 38 and then slipping the head of the kingpin from the slot 35. It should be noted that the particular connection of the kingpins with the chassis is capable of general application. Similarly, the particular locking device at the bottom end of the kingpin, which includes the screw 51, is capable of general application.

It is believed that the complete action of the skate will be clear from the description at the beginning of this specification, and the description of the construction of the skate.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a roller skate, a chassis having a top strip portion provided with a front lug and a downwardly directed sharp edge to the rear of

said front lug and also having a central portion provided with a front sharp edge located downwardly and rearwardly of said first named sharp edge, said second named sharp edge being disposed at an inclination to face forwardly and downwardly, a hanger for a skate truck having a substantially horizontal central seat beneath said top strip portion and an upwardly and forwardly extending front arm engaging said first named sharp edge and a substantially horizontal rear arm engaging said bottom sharp edge, and a kingpin connected with said top strip portion and extending downwardly and provided with connecting and holding means for said hanger including a cushion cooperative with its central seat.

2. In a roller skate, a chassis having a top strip portion provided with a front lug and a downwardly directed sharp edge to the rear of said front lug and also having a central portion provided with a front sharp edge located downwardly and rearwardly of said first named sharp edge, said second named sharp edge being disposed at an inclination to face forwardly and downwardly, a hanger for a skate truck having a substantially horizontal central seat with a top shoulder and located beneath said top strip portion and an upwardly and forwardly extending front arm engaging said first named sharp edge and a substantially horizontal rear arm engaging said bottom sharp edge, a kingpin connected with said top strip portion and extending downwardly and provided with connecting and holding means for said hanger and cooperative with its central seat, and a cushion mounted on said kingpin and resting against the top shoulder of said central seat.

3. In a roller skate, a chassis having a top strip portion provided with a front lug and a downwardly directed sharp edge to the rear of said front lug and also having a central portion provided with a front sharp edge located downwardly and rearwardly of said first named sharp edge, said second named sharp edge being disposed at an inclination to face forwardly and downwardly, a hanger for a skate truck having a substantially horizontal central seat with a top shoulder and located beneath said top strip portion and an upwardly and forwardly extending front arm engaging said first named sharp edge and a substantially horizontal rear arm engaging said bottom sharp edge, a kingpin connected with said top strip portion and extending downwardly and provided with connecting holding means for said hanger and cooperative with its central seat, and a cushion mounted on said kingpin and resting against the top shoulder of said central seat, said central seat having a curved top surface for said cushion for firmly engaging it at the front and rear portion.

4. In a roller skate, a chassis having a top strip portion provided with a front lug and a downwardly directed sharp edge to the rear of said front lug and also having a central portion provided with a front sharp edge located downwardly and rearwardly of said first named sharp edge, said second named sharp edge being disposed at an inclination to face forwardly and downwardly, a hanger for a skate truck having a substantially horizontal central seat with a top shoulder and located beneath said top strip portion and an upwardly and forwardly extending front arm engaging said first named sharp edge and a substantially horizontal rear arm engaging said bottom sharp edge, a kingpin connected with

10 said top strip portion and extending downwardly and provided with connecting holding means for said hanger and cooperative with its central seat, and a cushion mounted on said kingpin and resting against the top shoulder of said central seat, said central seat having a curved top surface for said cushion for firmly engaging it at the front and rear portion, said central seat and cushion being of oval shape with its major axis extending longitudinally of the skate.

5. In a roller skate, a chassis having a top strip portion provided with a front lug and a downwardly directed sharp edge to the rear of said front lug and also having a central portion provided with a front sharp edge located downwardly and rearwardly of said first named sharp edge, said second named sharp edge being disposed at an inclination to face forwardly and downwardly, a hanger for a skate truck having a substantially horizontal central seat with a top shoulder and located beneath said top strip portion and an upwardly and forwardly extending front arm engaging said first named sharp edge and a substantially horizontal rear arm engaging said bottom sharp edge, a kingpin connected with said top strip portion and extending downwardly and provided with connecting holding means for said hanger and cooperative with its central seat, and a cushion mounted on said kingpin and resting against the top shoulder of said central seat, said central seat having a curved top surface for said cushion for firmly engaging it at the front and rear portion, said central seat and cushion being of oval shape with its major axis extending longitudinally of the skate, and said central seat having an elongated slot transversely thereof through which the kingpin passes.

6. In a roller skate, a chassis having a top strip portion provided with a front lug and a downwardly directed sharp edge to the rear of said front lug and also having a central portion provided with a front sharp edge located downwardly and rearwardly of said first named sharp edge, said second named sharp edge being disposed at an inclination to face forwardly and downwardly, a hanger for a skate truck having a substantially horizontal central seat with a top shoulder and located beneath said top strip portion and an upwardly and forwardly extending front arm engaging said first named sharp edge and a substantially horizontal rear arm engaging said bottom sharp edge, a kingpin connected with said top strip portion and extending downwardly and provided with connecting holding means for said hanger and cooperative with its central seat, and a cushion mounted on said kingpin and resting against the top shoulder of said central seat, said central seat having a curved top surface for said cushion for firmly engaging it at the front and rear portion, said central seat and cushion being of oval shape with its major axis extending longitudinally of the skate, said central seat having an elongated slot transversely thereof through which the kingpin passes, and an auxiliary cushion, washer and nut mounted on said kingpin beneath said hanger.

7. In a roller skate, a chassis having a top strip portion provided with a front lug and a downwardly directed sharp edge to the rear of said front lug and also having a central portion provided with a front sharp edge located downwardly and rearwardly of said first named sharp edge, said second named sharp edge being disposed at an inclination to face forwardly and downwardly,

a hanger for a skate truck having a substantially horizontal central seat with a top shoulder and located beneath said top strip portion and an upwardly and forwardly extending front arm engaging said first named sharp edge and a substantially horizontal rear arm engaging said bottom sharp edge, a kingpin connected with said top strip portion and extending downwardly and provided with connecting holding means for said hanger and cooperative with its central seat, and a cushion mounted on said kingpin and resting against the top shoulder of said central seat, said central seat having a curved top surface for said cushion for firmly engaging it at the front and rear portion, said central seat and cushion being of oval shape with its major axis extending longitudinally of the skate, said central seat having an elongated slot transversely thereof through which the kingpin passes, and an auxiliary cushion, washer and nut mounted on said kingpin beneath said hanger, the bottom seat of said hanger being curved in transverse cross section.

8. In a roller skate, a chassis having a top strip portion provided with a rear lug and a downwardly directed sharp edge to the front of said rear lug and also having a central portion provided with a rear sharp edge located downwardly and forwardly of said first named sharp edge, said second named sharp edge being disposed at an inclination to face rearwards and downwards, a hanger for a skate truck having a substantially horizontal central seat beneath said top strip portion and a substantially horizontal front arm engaging said second named sharp edge and an upwardly and rearwardly extending rear arm engaging said first named sharp edge, a kingpin connected with said top strip portion and extending downwardly to said central seat, and cushion means mounted on said kingpin and engaging said central seat.

9. In a roller skate, a chassis having a top strip portion provided with a rear lug and a downwardly directed sharp edge to the front of said rear lug and also having a central portion provided with a rear sharp edge located downwardly and forwardly of said first named sharp edge, said second named sharp edge being disposed at an inclination to face rearwards and downwards, a hanger for a skate truck having a substantially horizontal central seat beneath said top strip portion and a substantially horizontal front arm engaging said second named sharp edge and an upwardly and rearwardly extending rear arm engaging said first named sharp edge, a kingpin connected with said top strip portion and extending downwardly to said central seat, and cushion means mounted on said kingpin and engaging said central seat, said central seat having a top shoulder, and said cushion means having a cushion resting against said top shoulder.

10. In a roller skate, a chassis having a top strip portion provided with a rear lug and a downwardly directed sharp edge to the front of said rear lug and also having a central portion provided with a rear sharp edge located downwardly and forwardly of said first named sharp edge, said sec-

ond named sharp edge being disposed at an inclination to face rearwards and downwards, a hanger for a skate truck having a substantially horizontal central seat beneath said top strip portion and a substantially horizontal front arm engaging said second named sharp edge and an upwardly and rearwardly extending rear arm engaging said first named sharp edge, a kingpin connected with said top strip portion and extending downwardly to said central seat, and cushion means mounted on said kingpin and engaging said central seat, said central seat having a curved top surface, and said cushion means having a cushion engaging said top surface firmly at the front and rear portions thereof.

11. In a roller skate, a chassis having a top strip portion provided with a rear lug and a downwardly directed sharp edge to the front of said rear lug and also having a central portion provided with a rear sharp edge located downwardly and forwardly of said first named sharp edge, said second named sharp edge being disposed at an inclination to face rearwards and downwards, a hanger for a skate truck having a substantially horizontal central seat beneath said top strip portion and a substantially horizontal front arm engaging said second named sharp edge and an upwardly and rearwardly extending rear arm engaging said first named sharp edge, a kingpin connected with said top strip portion and extending downwardly to said central seat, and cushion means mounted on said kingpin and engaging said central seat, said central seat having a curved top surface, and said cushion means having a cushion engaging said top surface firmly at the front and rear portions thereof, said central seat and cushion being of oval shape with its major axis extending longitudinally of the skate.

12. In a roller skate, a chassis having a top strip portion provided with a rear lug and a downwardly directed sharp edge to the front of said rear lug and also having a central portion provided with a rear sharp edge located downwardly and forwardly of said first named sharp edge, said second named sharp edge being disposed at an inclination to face rearwards and downwards, a hanger for a skate truck having a substantially horizontal central seat beneath said top strip portion and a substantially horizontal front arm engaging said second named sharp edge and an upwardly and rearwardly extending rear arm engaging said first named sharp edge, a kingpin connected with said top strip portion and extending downwardly to said central seat, and cushion means mounted on said kingpin and engaging said central seat, said central seat having a curved top surface, and said cushion means having a cushion engaging said top surface firmly at the front and rear portions thereof, said central seat and cushion being of oval shape with its major axis extending longitudinally of the skate, said central seat having an elongated slot transversely thereof through which said kingpin passes, and an auxiliary cushion, washer and nut mounted on said kingpin beneath said hanger.

CHARLES ZIG. SHYE.
